UNITED STATES PATENT OFFICE.

WILLIAM H. PARKER AND GEORGE L. SMYTH, OF MONTREAL, QUEBEC, CANADA.

SLIDING DOOR.

1,394,216.

Specification of Letters Patent. Patented Oct. 18, 1921.

Application filed April 28, 1919. Serial No. 293,164.

To all whom it may concern:

Be it known that we, WILLIAM H. PARKER and GEORGE L. SMYTH, both subjects of the King of Great Britain, and both residents 5 of the city of Montreal, in the Province of Quebec and Dominion of Canada, have invented certain new and useful Improvements in Sliding Doors, of which the following is a full, clear, and exact description.

10 This invention relates to improvements in sliding door construction and the object is to provide a door which will slide smoothly and easily at all times.

A further object is to provide a door so 15 constructed that it will be impossible for it to escape from its proper path, as frequently occurs with existing sliding doors.

20 A still further object is to provide a door which will slide easily and freely, but will at the same time be substantially weather-tight.

25 Another object is to provide a door suitable for all cases in which sliding doors are used.

At the present time, the so called sliding doors are almost entirely suspended from a track by running wheels secured to the top of the door. The bottom of the door must be free from the floor and the door must 30 have guiding means at the bottom to keep it from swaying. In houses or other buildings, such construction necessitates the provision of very considerable recesses above the door for the reception of the track and running 35 wheels and, if the wheels jump the track, it is an extremely difficult matter to get them back on the track.

According to the present invention, no recesses are necessary in the wall above the 40 door when used in a house. The door runs between upper and lower tracks which engage grooves in the door edges, so that the door is held against swaying and against jumping off either track. The interengagement of the door groove and track makes 45 the door weather-tight. Running wheels are carried by the door at top and bottom to reduce friction between the door and tracks.

In the drawings which illustrate the invention:—

Figure 1 is a partial side elevation of a door.

Fig. 2 is a side elevation of one of the running wheels.

55 Fig. 3 is a section on the line 3—3, Fig. 2.

Referring more particularly to the drawings, 11 designates a door of any type which is provided adjacent the four corners with housings 12 each containing a running wheel 13. These wheels are adapted to cooperate 60 with tracks 14 located above and below the door. It will be understood that while running wheels are shown only at the four corners of the door that as many additional housings and running wheels may be provided 65 in the upper and lower edges of the door as are required. It will also be understood that while only a single running wheel has been shown in each housing two or more such wheels may be provided in each housing if desired.

In the form of the invention illustrated, the housing is formed partly by the door, which is recessed at 15 to receive the running wheel 13, and partly by a pair of plates 16 75 located one on each side of the door and closing the sides of the recess 15. These plates may be set into recesses 17 in the door so as to be flush with the surface thereof, as shown, or may be applied to the door without the provision of the recesses 17. The plates may be secured to the door or to one another by screws or bolts 18. The running wheel 13 may be secured between the plates of each pair in any suitable manner such as 80 by a pin 19 passing through the running wheel and plates. If the pin is screwed into the plates, as shown in Fig. 3, it will be advisable to provide a sleeve 20 around the pin, upon which the wheel may revolve and 85 which may be irrevolubly clamped between the plates by the pin 19, so that revolution of the wheel will not loosen the screwed-in pin. It will be understood that the running wheel may be supported in any other manner found 90 desirable. It will also be understood that, if desired, the plates 16 may be mortised into the material of the door so as to be completely concealed thereby.

The tracks, between which the door runs, 100 are each formed of a strip of metal rolled to approximately the cross section shown in Fig. 3 and having a large central rib 21 forming the rail head and flanked on each side by smaller ribs 22 separated from the 105 center rib 21 by grooves 23. The extreme edges of the track may be in the form of outwardly projecting flanges 24 adapted for securing the rails in place by any suitable means. It will be understood that the tracks 110

may if desired be rolled or cast solid instead of the hollow construction shown, providing the arrangement of ribs is retained.

The upper and lower edges of the door 5 are each provided with a groove 25 adapted to receive the center rib 21 of a rail and the running wheels are located to support the door, so that there is just a nice running clearance between the groove and the center 10 rib 21 of the rail and also between the un-grooved edge portion of the door and the ribs 22, as clearly shown in Fig. 3.

The features of operation of the door are the same regardless of the use to which the 15 door is put. The door is supported at both top and bottom edges by the deeply grooved running wheels engaging the track ribs 21, and is thereby positively held against swaying, such as occurs with the ordinary sliding 20 door which is supported only from the top. The door is supported from below, which is the logical point of support. The provision of the second rail above the door positively prevents it running off its supporting rail, 25 as frequently happens with doors supported from above. This is especially true of freight car doors, where the opening and closing force is applied very close to the lower edge of the door, so that the tendency 30 is to lift one of the running wheels at the top of the door off the track. The provision of grooves in the door edges to receive the rails makes the door weather-proof when used as an outside door and also substantially draft-proof when used as an inside 35 door.

We claim—

1. In a device of the class described, a door grooved at its upper and lower edges, 40 rails above and below the door each having a central rib entering the door groove, and smaller ribs on each side of the central rib.

2. In a device of the class described, a door recessed in its upper and lower edges adjacent to the corners to form pockets, 45 grooved running wheels revolvably mounted in said pockets, grooves in the upper and lower edges of the door in alinement with the wheel grooves, said door grooves being slightly wider and deeper than the wheel 50 grooves, and rails located above and below the door engaging in the wheel and door grooves and held from contact with the door grooves by the wheels.

3. An arrangement according to claim 2, 55 in which each pocket is provided with removable side walls.

4. A door having its upper and lower edges provided each with a central longitudinally extending groove and a pair of 60 upper and lower track plates having each a central rib adapted to project into the groove in the adjacent edge of the door and side ribs of less height than the central rib adapted to project into close proximity with the 65 ungrooved portion of the door edge, and grooved running wheels carried by the door for engagement with said central ribs, said wheels being arranged with the grooves thereof alined with the door grooves. 70

5. An arrangement according to claim 1, in which guiding and supporting rollers are located in the door groove to travel on the central ribs of the rails.

6. An arrangement according to claim 2, 75 in which each pocket is provided with removable side walls supporting and detachably connected with the wheel located within the pocket.

In witness whereof, we have hereunto set 80 our hands.

WILLIAM H. PARKER.
GEORGE L. SMYTH.
